UNITED STATES PATENT OFFICE.

DEYO W. PUTNAM, OF BUFFALO, NEW YORK.

KEY-HOLDER.

1,129,370.

Specification of Letters Patent. Patented May 11, 1915.

Application filed March 23, 1915. Serial No. 16,274.

To all whom it may concern:

Be it known that I, DEYO W. PUTNAM, a citizen of the United States of America, residing in the city of Buffalo, county of Erie, and State of New York, have invented certain new and useful Improvements in Key-Holders, of which the following is a full, clear, and exact description.

It is well known that when keys on a key ring are carried in the pocket of a garment, they soon abrade the material and cause the pocket to be worn through with the result that there is danger of losing the keys. To obviate this condition, I have provided a durable holder for the keys and key ring, in which the keys are drawn and frictionally held in place. The keys are easily removed from the holder by simply pressing its edges toward each other, and after being used may be quickly drawn up into the holder again. The keys are always attached to the holder and therefore they are not liable to become lost.

I have accomplished the above objects and advantages by the device shown in the accompanying drawings. In these drawings, like characters of reference indicate like parts throughout the several views, of which:

Figure 1 is a front elevation of my key holder with the keys extended and ready for use. Fig. 2 is a sectional elevation of the same taken on line 2--2 of Fig. 1. Fig. 3 is a front elevation of the same with the keys drawn up into the holder.

My device comprises a holder formed with a front 5 and a back 6 made of flexible material, preferably of leather or the like. The material forming the front and back of the holder is suitably stitched around three sides and is left open at one end. The back of the holder is provided with a slot 7 near the open end, and a slot 8 near the closed end. Passing through the slots 7 and 8 is a strap 9, which has its ends secured together by suitable fastening means 11. The ends of the strap are arranged so that a loop 12 is formed beneath the fastening means 11 for the reception of the key ring 13.

Extending around the three stitched sides of the holder is a resilient member 14, made preferably of spring wire. This member is disposed between the material forming the front and back of the holder and at the

edges thereof. A line of stitching 15, extending around the holder, just inside the resilient member, keeps the same in position. The portion of this member which extends across the closed end of the holder is provided with an offset 16, which is arranged just below the slot 8 at this end of the holder and forms a support or bearing for the strap 9.

Since the strap 9 has its ends secured together within the holder, it will be seen that an endless belt is formed passing through the slots 7 and 8. They key ring 13 carrying the keys 17, as hereinbefore described, is carried by the loop 12 in the end of the strap 9 and after the keys have been used they may be drawn up within the holder by grasping the strap at a point near the closed end of the holder and pulling toward the open end.

As resilient member 14 is arranged to stretch the material, forming the front and back 5 and 6, respectively, of the holder, it will keep these parts taut and cause the keys to be frictionally held up within the holder.

When it is desired to remove the keys from the holder, it is only necessary to grasp the holder so that the edges near the open end may be pressed toward each other, whereupon the frictional engagement of the sides of the holder with the keys will be released and the same will fall out of the holder by gravity and occupy the position shown in Fig. 1.

It will thus be seen that in my device I have provided a means for carrying keys wherein the key ring is never detached from the device, and in which they may always be easily accessible for use and quickly and conveniently drawn within the holder.

While I have shown and described my device for use in connection with keys, it is obvious that it may be used for any other suitable purpose, and I do not, therefore, wish to limit the application to the use herein shown and described.

Having thus described my invention, what I claim is:

1. A key holder comprising a front member and a back member stitched together at three sides, a resilient member secured around said stitched sides and an endless strap, for holding a key ring, slidably attached to said back member.

2. A key holder comprising a front member and a back member stitched together at three sides, a resilient member secured around said stitched sides and an endless strap, for holding a key ring, slidably attached to said back member and passing over said resilient member at the closed end of said holder.
3. A key holder comprising a front member and a back member stitched together at three sides, said back member being so formed as to provide a slot at each end thereof, an endless strap passing through said slots, and means for securing a key ring 10 to said strap.
4. A key holder comprising a front member and a back member stitched together at one end and at two sides, a resilient member, for keeping said front and back 20 members taut, extending across said stitched end and up each of said stitched sides and provided with an offset at said stitched end, an endless strap slidably attached to said back member and passing over said offset 25 in said resilient manner, and said strap be-
- ing so formed as to provide a loop for the reception of a key ring.
5. A key holder comprising a front member and a back member stitched together at one end and at two sides, said back member being formed so as to provide a slot at each end thereof, a resilient member, for keeping said front and back members taut, extending across said stitched end and up each of said stitched sides and provided with an offset at said stitched end and disposed directly beneath the slot at said stitched end, an endless strap slidably arranged through the slots of said back member and passing over said offset in said resilient member, and said strap being so formed as to provide a loop for the reception of a key ring.

In testimony whereof, I have hereunto signed my name in the presence of two subscribers.

DEYO W. PUTNAM.
